UNITED STATES PATENT OFFICE.

JAMES D. McGREGOR, OF BRANTFORD, ONTARIO, CANADA, ASSIGNOR TO BRANTFORD COMPUTING SCALES, LTD., OF BRANTFORD, CANADA, A CORPORATION OF CANADA.

DESIGN FOR A PRICE-SCALE CASING.

Application filed July 26, 1922. Serial No. 3,203. Term of patent 14 years.

To all whom it may concern:

Be it known that I, JAMES D. McGREGOR, a subject of the King of Great Britain, residing at Brantford, in the Province of Ontario and Dominion of Canada, have invented a new, original, and ornamental Design for A Price-Scale Casing, of which the following is a specification, reference being had to the accompanying drawing, forming part hereof.

Figure 1 is a perspective view taken from the front of the scale embodying the casing of my design;

Fig. 2 is a side view of the scale embodying the casing of my design; and

Fig. 3 is a rear view of the scale embodying the casing of my design.

I claim:

The ornamental design for a price scale casing as shown.

JAMES D. McGREGOR.
